(57) **CLAIM**

The ornamental design for a decorative bottle as shown and described.

DESCRIPTION

FIG. 1 is a top perspective view of a decorative bottle showing our new design.

FIG. 2 is a perspective view of thereof.

FIG. 3 is a perspective view of thereof.

FIG. 4 is a front view of thereof.

FIG. 5 is a rear view of thereof.

FIG. 6 is a first side view of thereof.

FIG. 7 is a second side view of thereof.

FIG. 8 is a top view of thereof; and,

FIG. 9 is a bottom view of thereof.

The broken lines illustrate unclaimed portions of the decorative bottle and form no part of the claimed design.

1 Claim, 9 Drawing Sheets
